UNITED STATES PATENT OFFICE.

RICHARD S. GILLESPIE AND HARRY JAMES, OF NEW YORK, N. Y.

PIPE-WRENCH.

SPECIFICATION forming part of Letters Patent No. 461,750, dated October 20, 1891.

Application filed June 25, 1891. Serial No. 397,460. (No model.)

To all whom it may concern:

Be it known that we, RICHARD S. GILLESPIE and HARRY JAMES, citizens of the United States, residing at New York, in the county 5 of New York and State of New York, have invented new and useful Improvements in Pipe-Wrenches, of which the following is a specification.

This invention has for its object to provide 10 a simple, strong, durable, and economical pipe-wrench which will quickly release and grip a pipe or other cylindrical object as the wrench is oscillated or reciprocated in the arc of a circle of which the pipe is the center. To accomplish this object our invention involves the 15 features of construction and the combination or arrangement of devices hereinafter described and claimed, reference being made to the accompanying drawings, in which—

20 Figure 1 is a sectional elevation of the improved wrench, showing a portion of the handle or lever broken away. Fig. 2 is a sectional view taken on the line xx , Fig. 1. Fig. 3 is a sectional elevation of a modified construction. Fig. 4 is a sectional view taken on the line yy , Fig. 3; and Fig. 5 is a sectional side elevation showing another modification.

In order to enable those skilled in the art 25 to make and use our invention, we will now proceed to describe the same in detail, referring to the drawings, wherein—

The numeral 1 indicates a box or yoke frame having one end wall provided on its inner surface with a projecting pivot-bearing 35 2, which, as here shown, is semicircular in cross-section and constitutes the support for an oscillatory handle or lever 3, suitably constructed in its front edge with a semicircular cavity or recess 4, accurately fitting upon the 40 pivotal bearing 2, all in such manner that the handle or lever can be oscillated to a limited extent upon the pivotal bearing as a center or fulcrum. The handle or lever is provided with a chamber 5, containing a pinion or gear 6, mounted on a transverse shaft or axle 7, which is supported at its extremities by the 45 side walls of the chamber. A shank 8, provided with an overhanging toothed jaw 9, is arranged to slide between the rear edge of the 50 handle or lever and the rear end wall of the box or yoke frame, and the front edge of the shank is provided with a series of teeth 10,

with which engage the teeth of the pinion or gear 6. The upper extremity of the handle or lever is formed or otherwise provided with 55 a series of teeth or serrations 12, which co-operate with the series of teeth or serrations 13, formed or otherwise provided on the jaw 9 of the bar or shank 8, so that if a pipe or other cylindrical object be inserted between 60 the teeth or serrations 12 and 13 and the handle or lever 3 be swung in the direction of the arrow 14 such handle or lever will turn on the semicircular or convex pivot-bearing 2 and cause the pinion or gear 6 to impart a 65 downward sliding movement to the shank 8 of the jaw 9, thereby causing the wrench to grip the pipe. At the same time the outermost portion of the toothed or serrated extremity 12 of the handle or lever 3 will move 70 toward the jaw 9, and consequently the pipe or other cylindrical object will be firmly gripped for the purpose of turning it in the desired direction. At the limit of the stroke the handle or lever is swung backward in the 75 direction of the arrow 15, and therefore the handle or lever will turn on the pivot-bearing 2 and cause the pinion or gear 6 to operate the shank 8 for releasing the pipe to obtain a fresh grip thereupon. By means of the pivot-bearing 80 2 and the pinion or gear 6, carried by the handle or lever 3, we are enabled to move the sliding bar or shank up and down a sufficient distance to afford a positive grip and release; but when the handle or lever is in its normal 85 position, as in Fig. 1, the bar or shank 8 can be freely raised or lowered its full length, because the pinion or gear can rotate on its shaft or axle.

In the modification, Fig. 3, the front edge 90 of the handle or lever 3 is formed with a cam or wedge shaped portion 16 at the lower extremity of the semicircular cavity or recess 4, and the handle or lever is hung upon a transverse pin or bolt 17, so that the handle or lever can be oscillated to a limited extent thereupon. The orifice 18 in the handle or lever is of a size somewhat larger than the diameter of the pin or bolt 17, and the rear edge of the handle or lever is formed or otherwise 95 provided with a series of longitudinal teeth 19, the sides of which converge toward the rear end wall of the box or yoke frame 1. The front edge of the sliding bar or shank 8 is 100

formed or otherwise provided with a series of longitudinal teeth 20, the sides of which converge toward the handle or lever and bear against the converging sides of the teeth 19, 5 all in such manner that when the handle or lever is swung in the direction of the arrow 21 the cam or wedge shaped projection 16, acting upon the semicircular pivot-bearing 2, forces the teeth 19 into engagement with 10 the teeth 20, and thereby causes the sliding bar or shank 8 to move downward for the purpose of gripping a pipe or other cylindrical object between the teeth or serrations 12 and 13. When the return stroke is imparted 15 to the handle in the direction of the arrow 22, the gripping action of the wrench is released for the purpose of obtaining a fresh grip upon the pipe or other object. The peculiar construction of the teeth 19 and 20 on 20 the converging sides, as described, prevents the teeth slipping upon each other under strain or pressure.

In the modification exhibited by Fig. 5 the handle or lever 3 is provided with a semicircular cavity or recess 4, accurately fitting the semicircular pivot-bearing 2 on the inside of the front end wall of the box or yoke-frame 1. The head of the handle or lever is constructed with a recess 23, in which is journaled a rotatable worm-gear 24, meshing into 25 the teeth 25 on the front edge of the sliding bar or shank 8, all in such manner that the worm-gear can be rotated for adjusting the jaw 9 to and from the teeth or serrations 12 30 on the handle or lever 3, while the positive grip and release is obtained through the movement of the handle or lever on the same principle as described with reference to Figs. 1 and 3.

35 In the several constructions illustrated the front end wall of the box or yoke-frame is provided at its inner side with a pivot-bear-

ing engaging the front edge of the oscillatory handle or lever, and the latter has a toothed engagement at its rear portion with the sliding bar or shank of the adjustable jaw 9, by which means we provide a very simple, economical, and efficient pipe-wrench which will positively and quickly grip and release a pipe or other cylindrical object, as occasion may 50 demand.

Having thus described our invention, what we claim is—

1. The combination of a box or frame having one wall provided at its inside with a pivot-bearing, a sliding bar or shank provided with a jaw, and an oscillatory handle or lever having one edge engaging the pivot-bearing and its opposite edge in toothed engagement with the sliding bar or shank, substantially 55 as described.

2. The combination of a box or frame, an oscillatory handle or lever having a pivotal bearing within the box or frame and provided with a rotatable gear, and a sliding bar 60 or shank provided with a jaw and in toothed engagement with the gear, substantially as described.

3. The combination, with a box or frame, of an oscillatory handle or lever pivotally mounted in the box or frame and provided with a rotatable worm-gear, and a sliding bar or shank having a jaw and in toothed engagement with the worm-gear, substantially as described.

In testimony whereof we have hereunto set our hands and affixed our seals in presence of two subscribing witnesses.

RICHARD S. GILLESPIE. [L. S.]
HARRY JAMES. [L. S.]
